UNITED STATES PATENT OFFICE.

THEODORE DE LAGE VIGER, OF PORT CHESTER, NEW YORK.

RAIL-JOINT.

1,307,168.

Specification of Letters Patent. Patented June 17, 1919.

Application filed December 6, 1918. Serial No. 265,571.

To all whom it may concern:

Be it known that I, THEODORE DE LAGE VIGER, a citizen of the United States, residing at Port Chester, in the county of West-
5 chester and State of New York, have invented certain new and useful Improvements in Rail-Joints, of which the following is a specification.

This invention relates to rail joints and
10 its object is to provide simple and effective means for securely connecting the meeting ends of railway rails without the employment of the usual bolts, nuts and fish plates.

Another object is to provide a joint of this
15 character equipped with means for effecting a proper electric connection between the rails and to avoid hammering at the joint.

With the foregoing and other objects in view, which will appear as the description
20 proceeds, the invention resides in the combination and arrangement of parts and in the details of construction hereinafter described and claimed, it being understood that changes in the precise embodiment of
25 the invention herein disclosed may be made within the scope of what is claimed without departing from the spirit of the invention.

In the accompanying drawings:—
30 Figure 1 represents a perspective view of the rail joint constituting this invention with the parts shown disconnected and arranged in juxtaposition ready for assembling,

35 Fig. 2 is a transverse vertical section through the connected rails showing them riveted together, and

Fig. 3 is a detail sectional view showing the electrical connection for the rail ends.
40 In the embodiment illustrated two rail ends 1 and 10 are shown, having a connector 15 arranged between them. The rail end 1 has the usual web 2 with a bolt hole 3 extending transversely therethrough and
45 the usual base flanges 4.

The rail end 10 has a recess or socket 11 extending longitudinally inward from one end, the lower walls of said socket being flared as shown at 12, the socket being de-
50 signed to receive a tongue 16 projecting longitudinally from one end of the connector or chair member 15. This tongue 16 has beveled flanges as 17 conforming in shape to the flare or bevel 12 of the socket
55 11 and corresponds in height to said socket

so that when the connector 15 is engaged with the rail end 10 these members will snugly fit each other. The tongue 16 has a vertically disposed socket 18 at its free end opening through its upper edge in which is 60 designed to be mounted a coiled spring 19 having a cap 20 at its upper end so that when the tongue 16 is inserted in socket 11 the spring will force the cap 20 against the upper wall of said socket 11 and will bear at 65 its lower end against the bottom of socket 18 and thereby prevent vibratory movement of the parts and also insure perfect electrical connection between them.

The other end of the connector 15 has two 70 longitudinally extending laterally spaced upright walls 21 and a recess 22 extending laterally beneath the walls 21 designed to receive the web 2 and the flange 4 on the rail end 1. A plate 23 projecting longitudinally in advance of the upright walls 21 of member 15, and on which the flanges 4 of the rail end 1 are designed to rest when the parts are assembled is shown clearly in Figs. 1 and 2. These upright walls 21 have their 80 upper edges beveled downwardly and inwardly as shown at 21' to receive the lower faces of the tread of the rail end 1 as is shown clearly in Fig. 2 so that a smooth tight fit between the parts will be assured. 85

These walls 21 are also provided with registering holes 24 which when the rail end 1 is inserted between said walls register with the hole 3 to receive connecting rivets 25 for rigidly attaching the connector 15 to the 90 rail end 1. While rivets are shown, they obviously may be dispensed with and these parts welded together if found desirable.

From the above description it will be obvious that a rail joint constructed as described and shown will form a solid rail joint, the parts of which are securely held connected without the use of fish plates, and the coiled spring 19 operates as a cushion to prevent hammering at the joint. 100

From the foregoing description, taken in connection with the accompanying drawings, the advantages of the construction and of the method of operation will be readily apparent to those skilled in the art to which 105 the invention appertains and while I have described the principle of operation of the invention together with the device which I now consider to be the best embodiment thereof, I desire to have it understood that 110

the device shown is merely illustrative and that such changes may be made as are within the scope of the claimed invention.

Having thus fully described my invention, what I claim as new and desire to secure by Letters Patent, is:—

1. A rail joint comprising two meeting rail ends, one having a longitudinally extending tongue of a height corresponding to 10 that of its web, and the other end having a recess to receive said tongue opening through the base of said rail, said tongue having a socket in its upper face, a coiled spring in said socket and projecting above 15 the upper face of said tongue, and a cap on said projecting spring end to yieldably engage the top wall of said recess.
2. A rail joint comprising two rail ends to be united, one having a longitudinally

extending recess opening through one end 20 and through its lower face, a connector for said ends having at one end a longitudinally extending tongue to enter said recess, a pair of laterally spaced longitudinally extending fingers at the other end of said connector 25 spaced apart a distance equal to the thickness of the web of the other rail end, and adapted to straddle said web, the upper edges of said fingers being beveled to fit the under faces of the tread of the adjacent 30 rail end.

In testimony whereof I affix my signature in presence of two witnesses.

THEODORE DE LAGE VIGER.
